UNITED STATES PATENT OFFICE.

WILLY ALFRED CARL SELKE, OF BERLIN, GERMANY.

PHOTOSCULPTURE APPARATUS.

SPECIFICATION forming part of Letters Patent No. 675,417, dated June 4, 1901.

Application filed January 20, 1898. Serial No. 667,251. (No model.)

To all whom it may concern:

Be it known that I, WILLY ALFRED CARL SELKE, a subject of the German Emperor, and a resident of Berlin, Germany, have invented 5 certain new and useful Photosculpture Apparatus for the Reproduction of Bodily Forms by Means of Photography, of which the following is a specification.

This invention allows of the production of 10 a plastic representation in relief or in full model of any solid form, and more especially of living persons, by means of a process based upon the use of photography in the manner hereinafter described.

15 The principle of this invention consists in making from the model to be represented by means of a kinematograph or consecutive-view apparatus a series of photographs which 20 respectively represent so much of the form as lies between the sensitive film and a definite plane parallel thereto, said plane being shifted for each photograph, so as to intersect the model more or less close to the camera, so that from the silhouettes or outlines of such 25 photographs, which are afterward placed with regard to one another in proper relative position and in respective planes corresponding to the planes of intersection on the model, there may be reproduced a relief or representation 30 of the form of the original model.

The annexed drawing represents a perspective view of the apparatus.

A carriage 1 carries the lights 2, which may be of any number, all in one plane, to which 35 the axis of the lens of the photographic apparatus 4 is perpendicular, and a light-screen 3 of such a kind that its edge is in the same plane as the lights 2.

The model to be photographed (represented 40 in the figure by a cone) is placed—as at 6, for instance—within the screen 3, and it is necessary that there shall be relative movement between the model and the carriage, so that the plane in which are the lights 2 and the 45 edge of the screen 3 may be caused to intersect the model at different distances from that point of the model which is nearest the photographic apparatus. For this purpose the carriage may be connected with the photographic 50 apparatus 4 in any manner—for instance, by means of a chain 5—so that when the photographic apparatus is set in action for taking

successive photographs the carriage may be simultaneously moved to a different distance from the photographic apparatus. The photographic apparatus which is preferably employed is a kinematographic or similar apparatus of any known construction which is adapted to take a series of photographs in rapid succession. The construction of said apparatus forming no part of the present invention is not illustrated in the drawing. It will be sufficient to say that the pulley *c* moves in correspondence with the action of the photographic apparatus and by means of the 55 chain 5, passing over pulleys *a b c*, moves the carriage 1.

The operation of the foregoing apparatus is as follows: The carriage is so placed that rays from the light 2 do not yet touch the 60 model. The photographic apparatus 4 is set in action, and by means of the chain 5 the carriage, with the lights 2 and screen 3, is moved simultaneously rearward, so that the light which passes the edge of the screen 3 65 illuminates the model gradually from the front rearward—that is to say, so much of the model as lies forwardly of the vertical plane *x x* containing the edge of the screen 3 and the lights 2. This plane moving in successive 70 stages rearward thus brings successively into the field of illumination more and more of the surface of the model 6 until all the surface of the model that would be visible from the camera-lens is brought into illumination, 75 always observing that the limiting line between the eclipsed and illuminated portions of the surface lies in a plane to which the axis of the camera-lens is perpendicular. During this movement the photographic 80 mechanism takes a series of successive photographs of the model. It will thus be understood that the photographs successively taken will each represent so much of the model as was illuminated at the moment it 85 was taken. Thus the outline of each part photographed will coincide with the plane *x x* of the limit of illumination at the time the photograph was taken. The series of photographs thus obtained can be used in different 90 ways. For example, by developing them as negatives and blacking out the details within the aforesaid outlines silhouettes are formed 95 corresponding each to the outline at the 100

plane $\alpha\alpha$ in different positions of said plane, and consequently the series of silhouettes is usable by superposition at proper distances to reproduce the outlines for the successive positions of the plane $\alpha\alpha$. Thus by cutting out the silhouettes singly and putting them together in their proper succession and relative position there is produced a form, the intervals of which are then filled up with a plastic material, or to make a relief reproduction by the gelatin method the negatives obtained can be exposed successively over one and the same photographic plate, and by printing, for instance, from the latter on a chrome-gelatin layer and by swelling the gelatin a plastic form in relief is obtained.

To produce all round modeled bodies—for instance, busts—by the above apparatus, it is necessary to take two series of photographs, one of the front of the model and one of the back of the same, and to unite the reproductions of the two series together.

What I claim is—

1. In an apparatus for the plastic imitation of a model by means of photography the combination of a plurality of lights in the same plane, and a screen having its edge in said plane, with a photographic apparatus having its axis perpendicular to said plane and means for the relative movement of the model and of the lights and screen in the direction of the axis of the photographic apparatus, substan-

tially as described and for the purpose indicated.

2. In an apparatus for the plastic imitation of a model by means of photography, the combination of a carriage, a plurality of lights, in one and the same perpendicular plane thereon and a screen therein, having its edge in said plane, with a photographic apparatus and means for the relative movement of the said carriage and of the model in the direction of the axis of the photographic apparatus, substantially as described and for the purpose indicated. 35

3. In an apparatus for the plastic imitation of a model by means of photography, the combination of a movable carriage, a plurality of lights in one plane thereon, and a screen having its edge in the same plane; together with a photographic apparatus, adapted to take a series of consecutive photographs and means connecting said consecutive photographic apparatus with the movable carriage and adapted to move the said carriage in accordance 50 with the successive photographs of the said model substantially as described and for the purpose indicated. 40

In witness whereof I have signed this specification in the presence of two witnesses.

WILLY ALFRED CARL SELKE.
